Primary Examiner — Ian Simmons*Assistant Examiner* — Shannon Weekley(74) Attorney, Agent, or Firm — Birch, Stewart, Kolasch & Birch, LLP(57) CLAIM

The ornamental design for a cookie cutter, as shown and described.

DESCRIPTION

FIG. 1 is a top perspective view of a cookie cutter showing my new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines in FIGS. 1 and 2 of the cookie cutter is for the purpose of illustrating environment, and forms no part of the claimed design.
